PRINTING TELEGRAPH APPARATUS

Reginald Dennis Salmon and Leslie Bernard Salmon, Croydon, England, assignors to Creed and Company Limited, Croydon, England, a British company

Application February 25, 1954, Serial No. 412,501

Claims priority, application Great Britain March 31, 1953

3 Claims. (Cl. 178—2)

This invention relates to telegraphic apparatus.

Apparatus is known in which one or more message transmitters controlled by tape record material is or are associated with a message-numbering transmitter which sends an identifying serial number preceding each message from said message transmitter or transmitters.

In a known form of this kind of apparatus the message-numbering transmitter is controlled by a tape perforated with a succession of serial numbers. When a tape is inserted in a message transmitter the first action is to start up the message-numbering transmitter which sends a figure-shift signal, one or more figure signals and a letter-shift signal. The presence of the letter-shift signal is automatically recognised and results in the automatic starting up of a message transmitter. In the form of tape controlled transmitter hitherto used in this apparatus the peckers for sensing the perforations in the tape are raised simultaneously and their position is read off sequentially for transmission of the signal combination represented by the perforations. The presence of the letter-shift signal combination in the tape is recognised by the fact that all five peckers are raised to their full extent.

One object of the present invention is to provide the same facilities in the case in which the tape controlled transmitters are of the type in which the peckers for sensing the tape are allowed to rise sequentially.

Another object of the invention is to extend the facility with such transmitters to enable a message numbering transmitter to be used for sending a serial designation which contains both letters and figures. In such case the letter-shift combination must be used as part of the serial designation and the only practicable way of separating serial designation is by a portion of blank tape. The present invention can be used to recognise such portion.

According to the present invention an arrangement for recognising the presence of a combination of elements, all of one kind, in perforated tape passing through a tape transmitter comprises an operating circuit for a relay including the transmitting contacts of the transmitter, which circuit is arranged to operate the relay on the occurrence of any element of another kind in the signal combination, a locking circuit for said relay, means for opening said locking circuit during a start element preceding a signal combination, and means operative during a stop element succeeding a signal combination for recognising the condition of said relay.

In carrying out the invention as applied to the association of a message-numbering transmitter with one or more message transmitters, each of the transmitters is preferably modified so that the cam sleeve controlling the peckers is driven through a magnet controlled clutch and is provided in known manner with a pecker to sense the presence of tape in the transmitter. A manually operated plunger which closes contacts for starting the sequence of operations, namely transmission of a message-identification number followed by transmission of a message, is also associated with each message transmitter so

2

that contacts operated by the plunger are also operated by the above mentioned pecker.

The operation of the invention will be understood from the following description taken in conjunction with the accompanying drawings in which:

Fig. 1 shows the circuits of a message-numbering transmitter for recognising the presence of a letter-shift perforation in the tape;

Figs. 2 and 3 show the circuits of respective message transmitters, associated with the message-numbering transmitter of Fig. 1.

Fig. 4 shows the circuits of Fig. 1 modified for recognising the presence of a portion of blank tape.

Referring to the drawings and first to Figs. 1 to 3, the three transmitters are of the kind described in U. S. Patent No. 1,773,866, issued August 26, 1930, but modified by the control shaft being driven through a clutch controlled by a clutch magnet. The clutch magnets are denoted CM1, CM2, and CM3 respectively. The cam sleeve is driven only when the clutch magnet is energised. The transmitting contacts of the three transmitters are shown at TC1, TC2 and TC3 respectively. The outgoing line is shown at L, Fig. 3 and is connected to the moveable contact tongue of contacts TC3. The normal position of these transmitting contacts is mark, denoted by M.

Each of the message transmitters Figs. 2 and 3 is provided with a manually operable plunger key TOA or TOB operating the contacts shown when depressed. This plunger can be locked in depressed position. Attached to the upper contact blade operated by each plunger is a pecker P2 or P3 which rests against the underside of the tape in the transmitter.

Operation of the apparatus will first be described when using the message transmitter of Fig. 2 and the associated message-numbering transmitter of Fig. 1.

The operator first fully depresses and locks the plunger key TOA. Contacts 1 and 2 and also 4 and 5 are closed. Relay AA is operated from negative battery, over contacts c1, winding of AA, contacts 1 and 2 of TOA to ground. Relay AA locks over its own operated contacts aa1, back contacts d1 to ground (relays C and D to which contacts c1 and d1 belong are shown in Fig. 1).

The message tape is then inserted into the transmitter and the plunger key TOA released. Contacts 1, 2 of this key open and contacts 2, 3 are closed. Contacts 4, 5 are kept closed by the pecker P2 resting on the underside of the tape.

Relay BA operates from negative battery over back contacts bb4 (of relay BB Fig. 3) front contacts aa2, contacts 5, 4, 3 and 2 of key TOA, ground. Relay BA locks itself over its contacts ba1 independently of relay AA.

The clutch magnet CM1 (Fig. 1) of the message-numbering transmitter is energised from negative battery, back contacts c3, winding CM1, front contacts ba2, aa3, and ground.

The message-numbering transmitter is provided with pairs of cam-operated contacts, such as SS1 and SS2. In the arrangement shown contacts SS1 are normally closed but are open during the sending of the start element and for a few milliseconds thereafter. Contacts SS2 are normally open but are closed for the latter half of No. 5 element and for the first part of the sending of the stop element.

The energisation of the clutch magnet CM1 causes the operation of the message-numbering transmitter. Signal combinations perforated in the tape can consist of a figure-shift signal, followed by one or more figures, followed by the letter-shift signal.

The relay HS shown is a high speed relay having two windings. One side of the right hand winding is connected

over contacts SS1 to marking potential, the other side of this winding being connected to the tongue of transmitting contacts TC1.

Every signal combination (other than the letter shift combination) contains at least one spacing element so that once at least during the transmission of the elements of a signal combination (i. e. the elements transmitted between the start element and the stop element) a circuit is closed for relay HS. This relay therefore operates once for each character transmitted. When operated it locks over its left hand winding and contacts hs1. This locking circuit is however interrupted at contacts SS1, during the sending of the start element.

During the sending of a letter-shift signal, which is an all-marking combination, no circuit is closed for relay HS and, during the sending of the stop element succeeding a letter-shift, relay C operates over contacts SS2, and back contacts hs1. Contacts c1, Fig. 2 thereupon open, relay AA de-energises and opens its contacts. The opening of contacts c3 and aa3, Fig. 1 breaks the circuit of clutch magnet CM1 and the message-numbering transmitter (Fig. 1) comes to rest. Closing of back contacts aa1, Fig. 2, prepares a circuit for the clutch magnet CM2 of the message transmitter, Fig. 2 which is completed by back contact c1 when relay C is released. The tape is automatically fed through the message transmitter and contacts TC2 transmit the message signals to line L.

At the end of the message the tape will pass out of the transmitter, the pecker P2 will, in the absence of tape, rise to open contacts 4 and 5 of TOA. The circuit of relay BA is broken. Contacts ba3 are opened and the clutch magnet CM2 de-energised.

In order to allow a second message transmitter, Fig. 3 to be used with the message-numbering transmitter of Fig. 1, the circuit of relay BA Fig. 2 includes back contacts bb4 of a relay BB of Fig. 3 and the circuit of relay BB includes back contacts ba4 of relay BA. The circuits of Figs. 2 and 3 are otherwise alike, the operating circuits of relays AA and AB each including a contact of relay D, Fig. 1.

When a tape is to be inserted in either message transmitter, the corresponding plunger key TOA or TOB is operated, tape is inserted in the transmitter and the plunger key released. A tape may thus be inserted in one of these transmitters whilst the other is operating. Assume that a tape is inserted in the transmitter Fig. 3 whilst that of Fig. 2 is operating. Relay AB is operated and locked. Relay BB cannot operate until relay BA is released. When relay BB operates the message-number transmitter is started and stopped as above described and when it stops and relay C is operated, relay AB is released by the opening of contacts c2 and the clutch magnet CM3 is operated when contacts c2 again close.

The message-numbering transmitter (Fig. 1) is provided with contacts TON which are closed when the tape runs out of the transmitter, by the action of a tape sensing pecker. These contacts are in the circuit of relay D and when the contacts are closed, relay D operates and opens contacts d1, Fig. 2, and contacts d2, Fig. 3, to prevent the respective message transmitters from operating, and closes contacts d3, Fig. 1, for an alarm bell B.

Fig. 4 shows the circuits of the message numbering transmitter in the case in which an all-spacing signal follows each serial number in the message-numbering tape to indicate the end of the number.

The relay HS is a high-speed relay having two windings. One side of the right-hand winding of relay HS is connected over contacts SS1, when closed, to spacing potential, the other side of this winding being connected to the tongue of transmitting contacts TC1.

Every signal combination (other than the "All-Spacing" combination) contains at least one marking element so that once at least during the transmission of the elements

of a signal combination (i. e. the elements transmitted between the start element and the stop element) a circuit is closed for relay HS. This relay therefore operates once for each character transmitted. When operated it locks over contacts SS3 its left-hand winding and contacts hs1. Contacts SS3 are open during the middle of the start element but are closed during the remaining part of the signal period. Thus during each start element relay HS is released and this relay is re-operated during the sending of a signal combination.

During the sending of an "all-spacing" signal, no circuit is closed for relay HS. During the sending of a stop element contacts SS2 are closed and if relay HS has not operated during the earlier part of the signal period, relay C operates over these contacts and back contacts hs1.

Contacts c1, Fig. 2, and c2 Fig. 3 thereupon open as previously described with the consequent release of relay AA and transmission of the message in the Message Transmitter.

While the principles of the invention have been described above in connection with specific embodiments, and particular modifications thereof, it is to be clearly understood that this description is made only by way of example and not as a limitation on the scope of the invention.

What we claim is:

1. A telegraph transmission control system for a plurality of interconnected automatic tape transmitters, said transmitters comprising a message numbering transmitter and a message transmitter, said numbering transmitter comprising sensing means for sensing the presence of a combination of signal code elements of identical character, said sensing means comprising a control relay, a pair of cyclically operated cam contacts under control of said numbering transmitter, transmitting contact means associated with said numbering transmitter, a first control circuit for said control relay including said transmitting contact means and one of said cam contacts, said control circuit completed at least once during every signal combination of unlike code elements transmitted by said numbering transmitter, said circuit opened during the signal combination of like elements, message transmitter operating control means, a second control circuit for controlling said last named means including the other of said cam controlled contacts and a contact under control of said control relay, whereby the presence of the code combination of identical elements initiates operation of said control means, and the cyclic operation of said second cam contact disconnects said control means.

2. A telegraph transmission control system as claimed in claim 1, wherein said control relay comprises a double winding relay, a first one of said windings included in said first control circuit, the other of said windings serially connected between said first cam contact and a contact associated with said control relay, said last named contact connected to lock said control relay in operated position independent of the position of said transmitting contact means.

3. A telegraph transmission control system as claimed in claim 2, further comprising a source of spacing potential and marking potential, said last named contact comprising a transfer contact having its tongue connected to said source of said spacing potential and adapted to apply said potential to said message transmitter operating control means when said control relay is deenergized.
